(57) **CLAIM**

The ornamental design for a fan and shroud assembly, as shown and described.

DESCRIPTION

FIG. 1 is a perspective front view;

FIG. 2 is a front view;

FIG. 3 is a left side view, with respect to FIG. 2;

FIG. 4 is a right side view, with respect to FIG. 2;

FIG. 5 is a rear view;

FIG. 6 is a top side view, with respect to FIG. 2;

FIG. 7 is a bottom side view, with respect to FIG. 2; and, FIG. 8 is a perspective rear view.

The broken lines in the drawings depict parts of the fan and shroud assembly that form no part of the claimed design.
